S. W. PARSONS

DOOR FASTENING DEVICE

Filed April 18, 1923

Inventor

Stuart W. Parsons.

By *T. May Lindley.* Attorney

UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

DOOR-FASTENING DEVICE.

Application filed April 18, 1923. Serial No. 632,857.

To all whom it may concern:

Be it known that I, STUART W. PARSONS, a citizen of the United States, and a resident of New Britain, in the county of Hartford, State of Connecticut, have invented certain new and useful Improvements in a Door-Fastening Device, of which the following is a specification.

This invention relates to door fastening devices.

A difficulty encountered in devising door fastening devices is that doors which are subject to weather conditions, such as in the case of garage doors and the like, become warped so that in closing them it is necessary to spring in either the top or bottom in order to tightly close the door space, and for this reason it has generally been the practice to provide a separate catch or fastening device for the top and bottom of the door. When using such an arrangement, considerable force must be applied in an inconvenient manner to first lock the top or the bottom, as the case may be, and then to spring and fasten the other side. It is, accordingly, an object of this invention to provide an improved form and arrangement for door fastening by which the top and bottom may be fastened simultaneously.

Another object of the invention is to provide an efficient device for fastening doors by which the force to close the door is applied through the fastening device itself.

Another object of the invention is to provide an improved form of door fastening device which may be adjustably fitted to a variety of varying heights of doors.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the appended claim.

In the drawing, in which is illustrated a door fastening device constructed in accordance with the practice of this invention and in which similar reference characters refer to similar parts—

Fig. 1 is an elevation showing the fastening device mounted on a door, and the members on the wall and door casing with which

the door fastening device cooperates to close the door;

Fig. 2 is a plan view taken along the line 2—2 and illustrating the manner in which certain portions of the device operate to force the door into closed position; and

Fig. 3 is a sectional view along the line 3—3, showing the means for holding the door fastening device in its open or closed position.

Referring to the drawing, the device comprises a rod *a* mounted vertically on a door *b* by means of recessed angle plates *c* and provided at either end with a claw *d*, the upper one of which engages a pin *e* mounted on the door casing and a pin *f* mounted in the floor for engagement by the lower claw and a handle *g* by means of which the rod *a* may be turned to engage the pins *e* and *f*.

The rod *a* is made in two sections 10 and 11 which are joined by means of the sleeve 12. Each of these sections is bored as at 13 to provide a number of bolt holes at varying distances from the ends of the rod. Near each end of the sleeve 12 there is provided a hole corresponding in size to the holes 13 so that a bolt 15 may be passed through one of the holes 13 and the hole 14 when in registry to lengthen or shorten the rod *a*. Generally centrally of the sleeve 12 there is provided a boss 16 upon which the handle *g* is pivotally mounted by means of a pin 17 passing through the handle and the boss. When it is desired to rotate the rod *a*, the handle *g* may be lifted to provide sufficient leverage. Being thus pivoted the handle may be dropped to be out of the way, and, additionally in this position the handle cooperates with a locking means herein-after described.

Each of the claws has its active or pin engaging edge 18 curved so as to form a cam surface which facilitates in closing the door in that the claws hook about the pins, so to speak, and force the door to full closed position when the handle is turned.

Bearings for the rod *a* are provided by angle plates *c* suitably apertured to receive bushings 20 replaceable when worn, which additionally provide a bearing for the upper claw member *d* by which the weight of the rod and apparatus attached thereto is supported. Additional bearings are provided by angle plates 21 placed intermediate

the main bearing members *c* by which the rod *a* is kept from bending out of alinement when pressure is applied to the handle *g*.

The pin *e*, which is located at the casing 5 for engagement with the claw *d*, is mounted on a plate 25. The plate 25 may be screwed or fastened in any suitable manner onto the door casing, and in such position that when the door is nearly closed and the claw *d* is 10 rotated by means of the rod *a* and the handle *g*, the end of the claw will engage therewith so as to draw the top of the door inwardly. The pin *f* is preferably embedded in a concrete floor adjacent the door jamb and is 15 held rigidly between two end plates 29 which form the top and bottom of an open sided box structure having a side plate 30 provided to join the end plates 29 to keep them in properly spaced relation. The side plate 20 30 also acts as a door stop. The pin *f* is engaged by the lower claw *d* in precisely the same manner as the upper pin *e* above described.

If the door *b* is warped somewhat, it may 25 be that the top or bottom will tend to spring outwardly when the door has been fastened and, therefore, it is desirable that, when the door has been pulled tightly shut, means be provided for holding the handle *g* to prevent reverse rotation of the rod *a* which 30 would release the claws *d*. To this end there is provided an angularly bent sheet metal member 32 shown in plan in Fig. 3 which is apertured to receive the sleeve 12 there- 35 through so that the member may be screwed or bolted to the door and extend horizontally adjacent the path of the handle *g*. Two notches are provided in the horizontally ex- 40 tending portion of the member 32 such as are indicated at 34 and 36 so that when the handle *g* is allowed to drop it will fall into one or the other of these notches and be held there. If the handle *g* be turned in its 45 door fastening position, it may be dropped into the notch 36, and if rotated to its disengaging position, it may be dropped in the notch 34, being held in either of these posi-

tions by the projection 37 separating the notches.

The handle *g* is preferably made of sheet 50 metal material, and has a face or body portion 40 with side ribs 41 extending at right angles thereto and ears 42 extending generally in the direction of the side ribs 41 but slightly therebeyond and apertured to receive the pivot pin 17. The metal is cut away slightly adjacent the ears 42 as indicated at 44 so as to permit the handle to assume a horizontal position at right angles to the rod *a*.

Thus, by the above described construction, are accomplished, among others, the objects hereinbefore referred to.

As many changes could be made in the above construction and many apparently 60 widely different embodiments of this invention could be made without departing from the scope thereof, it is intended that all matter contained in the above description or shown in the accompanying drawing shall 65 be interpreted as illustrative and not in a limiting sense.

It is also to be understood that the language used in the following claims is intended to cover all of the generic and specific 70 features of the invention herein described and all statements of the scope of the invention which, as a matter of language, might be said to fall therebetween.

I claim as my invention:

A door fastening device comprising a sleeve, rods connected to the opposite ends of the sleeve, bolt heads carried by the rods for engagement with fixed keepers, a bearing bracket for said sleeve having an outstanding projection with notches on the opposite edges thereof, and a handle pivoted on said sleeve to turn therewith and move the bolt heads into locking and released positions and to swing thereon into position to engage said notches and secure the bolt heads in said locking and released positions.

STUART W. PARSONS.
